CERVICAL TRACTION HALTER

Frank J. Nightingale, 3178 University Ave.,
San Diego, Calif. 92104

Filed Dec. 9, 1971, Ser. No. 206,594

Term of patent 14 years

Int. Cl. D24—04, 99
U.S. Cl. D83—1 E

Fig. 1

Fig. 2

Fig. 3

Fig. 4

FIG. 1 is a perspective view of a cervical traction halter, showing my new design.

FIG. 2 is an end elevational view as taken from the right hand side of FIG. 1.

FIG. 3 is a side elevational view of the side opposite to that visible in FIG. 1.

FIG. 4 is a bottom plan view thereof.

I claim:

The ornamental design for a cervical traction halter, as shown.
